UNITED STATES PATENT OFFICE

SAMUEL D. RUCKER, OF SAN FERNANDO, CALIFORNIA

METHOD OF AND APPARATUS FOR SATURATING SAND IN WATER

Substitute for application Serial No. 293,012, filed July 16, 1928. This application filed October 15, 1930.
Serial No. 488,981.

My invention relates to an improved method of and apparatus for saturating sand with water preparatory to mixing the sand with cement to form concrete, and my object, generally speaking, is to provide a method and apparatus for this purpose which will insure thorough and uniform saturation of the sand in a minimum amount of time, substantially without labor and at negligible expense.

This application is a substitute for Serial No. 293,012, filed July 16, 1928, for "Method of and apparatus for saturating sand in water".

With the foregoing and other purposes in view, my invention consists in the novel steps employed in carrying out my improved method and in the novel features of construction, combination and arrangement of parts of my apparatus as will be hereinafter more fully described, illustrated in the accompanying drawings and defined in the appended claims.

In the drawings, wherein like characters of reference denote corresponding parts in the different views:

Figure 1 is a side elevation of apparatus constructed in accordance with my invention; Fig. 2, an end elevation of the apparatus illustrated in Fig. 1; Fig. 3, a top plan view of the apparatus illustrated in Figs. 1 and 2; and Fig. 4, a fragmentary perspective view of the water spray pipes embodied in my apparatus.

Referring now to the drawings in detail, 10 designates a casing, preferably but not necessarily of rectangular shape as viewed in top plan, closed at its sides and ends at 12, 14, respectively, open at its top and bottom and having its side walls 12 extended upwardly above the top thereof and equipped at their upper ends with angle iron members 16 or with other suitable means serving to stiffen and to reinforce said walls 12 and at the same time to provide means whereby said casing may be secured as by means of bolts 18 to the bottom of a bunker indicated generally at 20 in sand receiving relation to a discharge opening in said bunker through which the flow of sand into

said casing may be controlled in any desired manner not entering into my invention.

Casing 10 fits snugly within the stop portion of a receptacle 22 which is closed at its sides and ends as at 24, 26, respectively, and has its open bottom normally closed by a door 28, said receptacle being supported by rods 30 which are mounted at their upper ends in suitable brackets 32 projecting from the sides 12 of the casing 10 and which pass loosely through openings in flanges 34 at the top of the receptacle and have units 36 threaded thereon and engaging against the bottom faces of said flanges, this arrangement providing, as is manifest, for vertical adjustment 65 to the receptacle 22 relative to the casing 10 simply by manipulation of said units 36, whereby the effective capacity of the container constituted by the casing 10 and receptacle 22 may readily be varied.

Supported in any suitable manner between the side walls 12, 12 of casing 10, near the upper ends of said side walls, is a series of deflector bars 38, said bars consisting preferably of lengths of angle iron arranged in parallel, spaced relation in a common horizontal plane and with their apex portions disposed upwardly, whereby sand gravitating from the bunker 20 upon said bars will be split by the latter into a number of relatively thin, 80 separated streams.

Directly beneath each bar 38 and extending parallel therewith is a water pipe 40 provided with longitudinally extending rows of apertures 42 through which water is adapted to be 85 discharged into the streams of sand flowing downward between the bars 38, said pipes being supported in any suitable manner and being connected to a common water supply pipe 44.

Below the pipes 40 is a second series of deflector bars 46 arranged in parallel, spaced relation directly beneath the spaces between the bars 38 whereby each stream of sand produced by said bars 38 is interrupted and divided into two smaller streams, one flowing to either side of each bar 46, which bars may 95 conveniently consist of lengths of angle iron like the bars 38 or of half sections of pipe as shown.

The door 28 is hinged as at 48 for swinging movement to and from closed and open positions and is urged constantly towards closed position by a weight or weights 50 or equivalent means, being maintained normally in closed position by a latch element 52 on a yieldable support 54 which is adapted to be engaged by a batch car traveling beneath the apparatus to disengage said latch and permit the door 28 to open and the influence of the weight of said contained within the receptacle 22, whereby the sand will be discharged into said car. A latch or latches 56 is or are provided on the receptacle 22 for engagement by any suitable part of the door 28 to hold the latter in an open position and the support 54 is formed of two sections hinged together in such manner as indicated at 58 that the latch element 52 will be released only by a car traveling in a direction to receive a load from the apparatus and not by a car traveling in a return direction.

In the side walls 24 of the receptacle 22 and, if desired, also in the end walls thereof, is formed a multiplicity of apertures 60 for the escape of any superabundance of water supplied to the sand during its travel from the bunker 20 into the receptacle 22.

In the use of my apparatus the receptacle 22 first is adjusted with respect to the casing 10 by means of the nets 36 to produce a container of a desired capacity. A valve controlling the flow of water to the pipes 40 then is opened and sand is permitted to gravitate from the bunker 20 into the apparatus. As the sand is intercepted by the bars 38 it is split as aforesaid into relatively thin streams against which upwardly directed jets of water issuing from certain of the apertures 42 in pipes 40 are directed, these jets of water penetrating the streams of sand and thoroughly saturating same. The streams of sand flowing downward then are intercepted by the bars 46 and are divided into thinner streams which directly receive downwardly directed jets of water from certain other of the apertures 42, the entire volume of sand flowing into the container thus being thoroughly broken up and uniformly saturated with water, any superabundance of which latter escapes through the openings 60 as the container becomes gradually filled with sand. When a desired quantity of sand accumulates within the container the supply of sand and water is cut off and the contents of the container allowed to flow through the lower open end of the receptacle 22 into a car or cars for transportation to a point where it is to be used, whereupon the operation which is recounted is repeated, it having been found in practice that the relative amounts of sand and water contained in different batches of these materials mixed by my improved method and apparatus are substantially unvarying.

What I claim as new and desire to secure by Letters Patent of the United States is as follows:

1. The method of mixing sand and water with one another which consists in flowing the sand in a stream, directing a jet of water against said stream, dividing the stream of sand into smaller streams, and directing other jets of water against said smaller streams. 75

2. Apparatus for use in mixing sand and water with one another comprising a container composed of telescoped elements adjustable to vary the effective capacity of said container, means for so adjusting said elements, said container being open at its top and being adapted to have sand supplied thereto from a point thereabove, means in the upper element of the container to divide sand being supplied to said receptacle into a number of relatively thin streams, and means also in the upper element of the container for directing jets of water against said streams. 80

3. Apparatus for use in mixing sand and water with one another comprising a container open at its top and adapted to have sand supplied thereto from a point thereabove, a horizontal series of spaced bars arranged to intercept sand being supplied to said container to divide said sand into a plurality of streams, a second horizontal series of bars located below said first mentioned series in vertical alignment with the spaces between the bars of said first series to intercept said streams of sand and divide them into smaller streams, and means between said series of bars for directing jets of water upwardly against said streams of sand produced by the first series of bars and for directing other streams of water downwardly against the streams of sand produced by the second series of bars. 85

4. Apparatus for use in mixing sand and water with one another comprising a casing, a receptacle below said casing slidably receiving in the upper end thereof the lower end portion of said casing, means for slidably adjusting said casing and said receptacle with respect to one another to vary the effective capacity of the container formed by said casing and said receptacle, means carried by said casing for dividing into streams sand being supplied to said container, means for saturating said streams of sand with water, and means whereby any superabundance of water contained in the sand deposited in said receptacle may flow therefrom. 105

In testimony whereof I affix my signature. 125

SAMUEL D. RUCKER.
